UNITED STATES PATENT OFFICE

142,195

DESIGN FOR A PREFORMED AIRPLANE HANGAR OR THE LIKE

John C. Radcliffe, Jr., Kirkwood, Mo.

Application March 1, 1945, Serial No. 118,193

Term of patent 14 years

(Cl. D13—1)

To all whom it may concern:

Be it known that the undersigned, John C. Radcliffe, Jr., a citizen of the United States, residing at Kirkwood, St. Louis County, Missouri, has invented a new, original, and ornamental Design for Preformed Airplane Hangar or the like, of which the following is a specification, reference being had to the accompanying drawing forming a part thereof, in which:

Fig. 1 is a front perspective view of a preformed or prefabricated airplane hangar showing the new design; and

Fig. 2 is a rear elevational view thereof.

The dominant features of my design for an airplane hanger reside in the full line drawing disclosures.

I claim:

The ornamental design for a preformed airplane hangar or the like, substantially as shown and described.

JOHN C. RADCLIFFE, JR.
